UNITED STATES PATENT OFFICE.

MAX AMS, OF NEW YORK, N. Y.

METAL CAN.

SPECIFICATION forming part of Letters Patent No. 402,882, dated May 7, 1889.

Application filed March 22, 1889. Serial No. 304,334. (No model.)

To all whom it may concern:

Be it known that I, MAX AMS, of New York city, New York, have invented an Improvement in Metal Cans, of which the following is 5 a specification.

This invention relates to an improvement in metal cans and boxes, and more particularly to the mechanism for opening the same.

The invention consists in the various features of improvement more fully pointed out in the claims.

In the accompanying drawings, Figure 1 is a side view of the upper part of a can provided with my improvement. Fig. 2 is a vertical central section through the same; Fig. 3, a side view showing it partly opened; Fig. 4, a section on line $x-x$; Fig. 1; and Fig. 5, a side view of a modification.

With particular reference to Figs. 1 to 4, 20 the letter a represents the body of a metal can or box, of suitable shape in cross-section, and having overlapping upright ends soldered one upon the other. The upper end of the box is preferably enlarged, as shown, it being 25 provided with an offset, a' .

b is the cover provided with a flange, b' , which is received within the upper part of the can above the offset a' , as shown in Fig. 2.

In order to provide for the ready opening of 30 the can, I interpose a separate strip of metal, c , between the two soldered edges of can a . This strip c projects partly outward and partly inward beyond the overlapping ends of the can. In manufacturing the can the strip c is 35 placed between such ends before the latter are soldered upon each other, and thus the same operation which joins the can-edges joins the strip c to the can-body.

In order to accommodate the inner or concealed end of the strip c , the body a may be 40 bulged slightly outward above such strip, as at a^2 in Fig. 4. After the can-body has been formed with the strip c in place the cover b is slipped into the upper end of the can-body 45 and its flange b' soldered thereto. The inner face of that part of strip c that projects into the can-body will also be soldered to flange b' by the same operation which connects the cover to the can. It will thus be seen that 50 the proper attachment of strip c involves but a very small amount of extra labor.

Beneath the strip c the body a may be weak-

ened by a circumferential indented line, d , having a cut-away end, d' .

In use the outwardly-projecting part of strip 55 c is grasped by a key or by the hand, and by it the upper part of the can-body is torn off, as in Fig. 3. It will be seen that after the overlapping ends of the can-body have been torn asunder above line d the inner end of 60 strip c is still attached to flange b' and must be torn from the latter. This prevents the strip from becoming entirely disconnected from the can by reason of the great strain placed upon it during the beginning of the 65 operation. Such strain will not have a tendency to disconnect the strip from body a , but from flange b' . After the can has been opened so far that the strip has been torn off the flange 70 b' , Fig. 3, there is no more danger of the strip 70 coming off the body a .

In Fig. 5 the flange b^2 of the cover overlaps the upper edge of body a , in lieu of being inclosed by the can-body. In this modification two indented lines, d^2 d^3 , are formed, 75 and between them the strip c is secured in such a way as to partly project beyond the overlapping ends of body a , as previously described. The concealed part of strip c is in this modification not soldered to the flange b^2 80 of the cover, but to the inner face of body a . Of course in this modification the strain on the strip c while opening the can will have a tendency to detach the strip from body a . In this respect the construction shown in Figs. 85 1 to 4 is to be preferred.

An important feature of this invention is that the strips c may be stamped out of small pieces of waste. Heretofore when the cans were opened by a projecting tongue made in 90 one piece with the can-blank a large amount of metal had to be wasted for the purpose of cutting out the tongue.

What I claim is—

1. The combination of a can-body having 95 overlapping upright ends, with a strip placed between such ends and projecting outwardly from the same, the ends being soldered to each other and to the strip, substantially as specified.

2. The combination of a can-body having overlapping upright ends, with a strip, c , placed 100 between such ends and projecting partly outwardly and partly inwardly from the same,

the ends being soldered to each other and to the strip, substantially as specified.

3. The combination of a can-body having overlapping ends, with cover *b*, having flange *b'*, that is received by the can-body, and with a strip *c*, placed between the overlapping ends, the strip *c* being soldered to flange *b'* and to the overlapping ends of the can-body, substantially as specified.

4. The combination of can-body *a*, having offset *a'* and indented line *d*, with the cover *b*, having flange *b'*, and with the strip *c*, secured partly to the can-body and partly to flange *b'*, substantially as specified.

MAX AMS.
